US00D965562S

(12) **United States Design Patent** (10) Patent No.: **US D965,562 S**
(45) Date of Patent: ** Oct. 4, 2022

(54) **ELECTRONIC DEVICE**

- (71) Applicant: **Apple Inc.**, Cupertino, CA (US)
- (72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)
- (73) Assignee: **Apple Inc.**, Cupertino, CA (US)
- (**) Term: **15 Years**
- (21) Appl. No.: **29/823,494**
- (22) Filed: **Jan. 18, 2022**

Related U.S. Application Data

(57) **CLAIM**

The ornamental design for an electronic device, as shown and described.

DESCRIPTION

FIG. 1 is a front perspective view of an electronic device showing our new design;

FIG. 2 is a rear perspective view thereof;

FIG. 3 is another front perspective view thereof;

FIG. 4 is another rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The dashed broken lines depict structure or features that form no part of the claimed design.

(Continued)

The oblique shade lines depict a glossy surface.
The stipple shading depicts a matte surface.

1 Claim, 5 Drawing Sheets

Related U.S. Application Data

continuation of application No. 29/658,595, filed on Aug. 1, 2018, now Pat. No. Des. 901,448, which is a continuation of application No. 29/617,528, filed on Sep. 14, 2017, now Pat. No. Des. 827,615, which is a continuation of application No. 29/578,397, filed on Sep. 21, 2016, now Pat. No. Des. 805,058, which is a continuation of application No. 29/526,019, filed on May 5, 2015, now Pat. No. Des. 771,597.
